UNITED STATES PATENT OFFICE.

EDGAR H. MUMFORD, DECEASED, LATE OF PLAINFIELD, NEW JERSEY, BY ROSE S. MUMFORD, EXECUTRIX, OF PLAINFIELD, NEW JERSEY.

MOLDING-MACHINE.

1,306,075.

Specification of Letters Patent. Patented June 10, 1919.

Application filed June 17, 1915. Serial No. 34,709.

To all whom it may concern:

Be it known that EDGAR H. MUMFORD, deceased, late a citizen of the United States, residing at Plainfield, in the county of Union 5 and State of New Jersey, did invent certain new and useful Improvements in Molding-Machines, of which the following is a specification.

This invention relates to molding machines, and it has for one of its primary objects the provision of a combined squeeze and jolt ramming molding machine of novel and simple construction. Another of the chief objects of his invention is the provision 15 of novel mechanism whereby well known types of squeezer molding machines, such for example as the Mumford squeezer machine, may be readily and inexpensively transformed into a combined squeeze and jolt ramming machine.

The foregoing, together with such other objects as may hereinafter appear or are incident to the invention, he attains by means 25 of a construction which he has illustrated in preferred form in the accompanying drawings, wherein:

Figure 1 is a perspective view of a squeeze machine of the Mumford type; Fig. 2 is an enlarged partial section of one form of valve 30 mechanism employed in carrying out the invention; Figs. 3 and 4 are respectively a plan and sectional view of a detail of the improvement; and Fig. 5 is an enlarged sectional view of a squeezer molding machine 35 of the type described, as transformed into a combined squeeze and jolt ramming machine by the introduction of the improved attachment.

The machine shown in Fig. 1 of the drawings is substantially the same as that shown in Fig. 6 of U. S. Letters Patent No. 932,563, issued to Edgar H. Mumford on August 31, 1909, and briefly considered, comprises a base A on which is swingingly mounted the 45 squeeze yoke B. At the top, the base A is provided with a plane flange portion or seat 7 to which the cylinder 8 is secured by means of the bolts 9. On the top of the cylinder 8 is a supporting frame 10 which carries the 50 pattern carrier mechanism C upon which the pattern is attached, the elevating frame D upon which the flask or mold rests, and by the movement of which the mold is freed from the pattern, and the fluid plunger 55 mechanism 6 by means of which the frame D

is elevated, as set forth in Letters Patent of the United States, No. 846,685, issued to Edgar H. Mumford on March 12, 1907. This type of machine is known as a squeezer in which the ramming or squeezing of the mold 60 is effected by advancing the mold parts toward and pressing them against the platen 11 of the ramming yoke.

This machine has gone into extensive use, and as previously indicated, one of the chief 65 objects of the present invention is the provision of novel and simple means whereby this machine may be effectively transformed into a combined squeeze and jolt ramming machine whereby the machine may be used 70 in carrying out jolt ramming operations without in the least impairing its functions and operation in carrying out a squeezing molding operation.

The foregoing is accomplished by inter- 75 posing between the parts of the machine just described certain elements which are shown in section in Fig. 5 in assembled relation. In changing over the machine, the frame 10 and its associated parts are detached from 80 the cylinder 8, and the cylinder 8 is detached from the base A by removing the bolts 9. A base plate 12 which is provided with an upstanding post or stationary plunger 13 is then mounted upon the flange 85 portion 7. The cylinder 8 is superimposed upon the base 12 and these parts are secured to the base A by means of the bolts 14, the plate 12 forming the bottom of the cylinder. A hollow plunger 15 is provided 90 which fits the bore of the cylinder 8 and which has a centrally disposed cylindrical portion 16 which fits the post 13. The plunger 15 is flanged at the top and the frame 95 10 of the squeeze machine to be transformed is secured thereto, an open joint being provided between the parts by means of the bosses 16'. Resting in the bottom of the cylinder beneath the lower face of the plunger 15 is a combined impact and valve member E such as shown and described in the Letters Patent issued to Edgar H. Mumford, No. 1,151,213, August 24th, 1915. In the bottom of the plunger are a plurality of 100 surge ports 17, the purpose of which will hereinafter appear. Fluid pressure is introduced into the cylinder 8 beneath the member E by means of a pipe 18, the supply of pressure being governed by any suitable 105 form of valve mechanism, not shown.

110

The guide post 13 is provided with a chamber 19 into which fluid pressure is introduced by means of the pipe 20, and detachably secured to the top of the post 13 by means of the studs 21 is a valve block 22. The valve block 22 is provided with a passage 23 for conducting the fluid pressure to the interior of the cylindrical portion 16 and a port 24 connects the end of 10 the passage 23 and the chamber 19. A valve 25 controls the passage 23. The foregoing mechanism is provided for carrying out jolt ramming operations of the machine, and the parts and their operation are the 15 same as those shown in Letters Patent No. 1,171,869, issued to Edgar H. Mumford Feb. 15, 1916. For the purposes of this specification, it will be sufficient to state that the operation of the machine as a jolt 20 rammer is as follows:

Fluid pressure is introduced into the chamber 19 through the pipe 20 and passes into the cylindrical portion 16 via the port 24 and passage 23, raising the cylindrical 25 portion 16 and the plunger 15 of which the cylindrical portion 16 forms a part, and thereby elevates the frame 10 and its associated parts. During this movement, the valve 25 remains in open position. When 30 the port 26 formed in the wall of the cylindrical portion 16 is uncovered by upward movement of the cylindrical portion 16, and the discharge end of the passage 23 is covered by the wall of the cylindrical 35 portion 16, the pressure in the cylinder exhausts through the port 26 and out through the open joint between the plunger 15 and the frame 10. As a result of the sudden reduction of pressure in the cylinder 40 which occurs upon the exhaust of fluid pressure in the chamber above the post through the port 26, the valve 25 moves upwardly, thereby cutting off the supply of fluid pressure. The parts then fall and the 45 plunger 15 impacts on the member E, thus jolting the mold. As the parts approach lower position, the tappet 27 in the top of the cylindrical portion 16 strikes the stem of the valve 25 and moves the latter to open position, thereby again admitting pressure into the cylinder. The 50 operation automatically repeats itself until the supply of pressure to the pipe 20 is manually cut off.

When the machine is being operated as a 55 squeezer, pressure is admitted through the pipe 18 into the bottom of the cylinder 8 and raises the member E and the plunger 15 and its associated parts, thereby advancing 60 the mold toward the platen of the yoke. It will be obvious that when the machine is being used to carry on a jolt ramming operation, there will be a tendency to draw a vacuum in the bottom of the cylinder 8 65 and to meet this difficulty, and to cause the

machine to operate smoothly and effectively, he has provided the surge ports 17 which permit the air to circulate freely in the cylinder during such operation. The air flows freely through the port 17 because 70 the member E during the jolt ramming operation lies in the bottom of the cylinder 8. Whenever the machine is used in carrying out a squeezing operation, the pressure introduced into the cylinder 8 beneath the 75 member E holds the latter in engagement with the bottom face of the plunger 15, thereby closing the surge ports 17. The member E therefore acts as a valve member during the squeezing operation and as 80 an impact member receiving the impact of the plunger during a jolt ramming operation.

It will be seen from the foregoing that a standard squeezer machine can be simply 85 and inexpensively transformed into a combined squeeze and jolt ramming machine, and that when thus transformed, either a squeezing operation or a jolt ramming operation can be effectively carried on. The 90 improvement is simple in construction and efficient in operation, and lends itself readily to adaptation to standard types of squeezer machines. It is inexpensive and effective in operation. 95

Claims:

1. An attachment for changing a squeezer molding machine having a base and a squeezer cylinder into a combined jolt and squeeze ramming molding machine, comprising a member adapted to be mounted on the base between the cylinder and the base, said member being provided with an upstanding post, a plunger member adapted to fit said squeezer cylinder and provided with a cylindrical portion adapted to fit said post, and means for introducing fluid pressure under the plunger member for a squeeze operation and between the plunger member and the upstanding post for a jolt 100 operation.

2. An attachment for changing a squeezer molding machine having a base and a squeezer cylinder into a combined jolt and squeeze ramming molding machine, comprising a cylindrical post member adapted to be carried on the base within the squeezer cylinder, a plunger adapted to fit said cylinder and having a cylindrical portion adapted to fit said post, and means for introducing fluid pressure under the plunger member for a squeezing operation and between the plunger member and the upstanding post for a jolting operation. 115

3. An attachment for changing a squeezer molding machine having a base and a squeezer cylinder into a combined jolt and squeeze ramming machine, comprising a cylindrical post member adapted to be carried on the base within the cylinder, a 125

plunger adapted to fit said cylinder and having a cylindrical portion adapted to fit said post, valve mechanism between said post and said cylindrical portion, and means 5 for introducing fluid pressure under the plunger member for a squeezing operation and between the plunger member and the upstanding post for a jolting operation, said valve mechanism controlling the fluid

pressure introduced between the plunger 10 member and the upstanding post.

In testimony whereof I have hereunto signed my name.

ROSE S. MUMFORD,
*Executrix of the estate of Edgar H. Mum-
ford, deceased.*
